WIRE GATE

Filed March 22, 1928

Inventor:
Frank J. Schlies Jr.
Signature:
C. W. Morrissey

UNITED STATES PATENT OFFICE.

FRANK J. SCHLIES, JR., OF MANITOWOC, WISCONSIN.

WIRE GATE.

Application filed March 22, 1928. Serial No. 263,827.

This invention relates to improvements in gates, and has primarily for its object to provide a simple, efficient, and inexpensive device capable of rendering a portion of an ordinary wire fence available as a gate, and which at the same time may function as a wire tightener.

Incidental to the foregoing, a more specific object is to provide a device adapted to be secured to the free ends of a section of wire fence, and provided with adjustable means for detachably engaging an adjacent post to hold the wire taut.

With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

In the drawings, the single figure is an elevation of a section of wire fence with the present invention applied thereto, parts being broken away and in section to more clearly illustrate the structural features.

Referring now more particularly to the accompanying drawings, wherein the invention is shown attached to a section of a conventional wire fencing, the numerals 1 designate spaced fence posts, which may be of any desired type, such as wood, metal, or concrete, and secured to the posts by staples 2, or other suitable means, are the usual horizontal stretches of wire 3.

As set forth in the objects, the present invention is designed to render a section of wire fence available as a gate, thus eliminating expense of installing the customary types of rigid gate structures. This is particularly desirable in instances where entrance through the fence is only seldom required.

To accomplish the foregoing, I provide a frame 4, consisting of the vertical side members 5 secured together by the lateral stretches 6, and the central cross members 7,

which members, in addition to bracing the frame, serve to carry a pivotal lever 8, the purpose of which will be later described.

As illustrated in the drawing, the stretches of the fence wire 3 are left free at one end and are secured to one of the vertical side members 5 in any suitable manner. The opposite side frame 5 is provided with brackets 9 to which are pivoted bell cranks 10, one arm of each being connected to the pivotal lever 8 upon opposite sides of its axis by means of a link 11. The opposite arm of each bell crank has pivoted thereto the hook 12 adapted to engage an eye, or other suitable projection, 13, carried by the adjacent fence post, 1. For the purpose of locking the pivotal lever 8 in any one of its adjusted positions, a detent 14 is secured to the frame 14 and provided with notches engaged by the spring-urged dog 15 carried by the pivotal lever.

The single view illustrates the present invention in operative closed position. To open the section of fence between the post 1, to render access therethrough, it is merely necessary to rotate the lever 8, which in turn rocks the bell cranks 10 upon their pivots and relieves tautness between the fence section, to the extent of permitting the hooks 12 to be disengaged from the eyes 13. The wire section can then be lifted to one side permitting any desired opening through the fence within the limits of the post. Closing of the fence section is obtained by a reverse operation.

From the foregoing it will be seen that a very simple and efficient device has been provided, to permit access through a section of wire fence, thus avoiding the necessity of gates and their incidental upkeep.

It will further be appreciated that after the device is positioned in closed operative position, any desired tautness of the fence section can be obtained by adjustment of the lever 8, which, through the link and bell crank connection, serves as a takeup. Further, the present type of gate eliminates strain upon the fence post from excessive weight, and, therefore, does not require the usual bracing.

I claim:

1. A device for attachment to the free ends of a section of wire fence comprising, a frame, a bell crank carried by said frame, a hook pivoted to one arm of said bell crank

for engaging a fence post, an adjustable lever carried by the frame, and a link connecting said bell crank and adjustable lever.

2. A device for adjustment to the free ends 5 of a section of wire fence comprising, a frame, a pair of spaced bell cranks carried by said frame, a hook pivoted to one arm of each bell crank for engagement with a fence

post, a lever pivotally carried by said frame, links connecting said bell cranks with said 10 adjustable lever, and a detent for locking said lever in adjusted position.

In testimony that I claim the foregoing I have hereunto set my hand at Madison, in the county of Dane and State of Wisconsin.

FRANK J. SCHLIES, JR.
